(57) **CLAIM**

We claim the ornamental design for the end tip for a shade system, as shown and described.

DESCRIPTION

FIG. 1 is a perspective view of the end tip for a shade system, shown in a configuration with the rod removed;

FIG. 2 is another perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof;

FIG. 9 is a perspective view thereof, shown in an assembled configuration;

FIG. 10 is another perspective view thereof;

FIG. 11 is a side view thereof, the left side view, the right side view, the front side view, and the back side view all being the same;

FIG. 12 is a top view thereof; and,

FIG. 13 is a bottom view thereof.

The broken lines in the drawings depict environment that form no part of the claimed design.
